United States Patent Office.

RICHARD H. RYNE, OF NEW YORK, N. Y., ASSIGNOR TO WILLIAM S. HICKS, OF SAME PLACE.

Letters Patent No. 62,227, dated February 19, 1867

PEN AND PENCIL-HOLDER.

The Schedule referred to in these Letters Patent and making part of the same.

TO ALL WHOM IT MAY CONCERN:

Be it known that I, RICHARD H. RYNE, of New York, in the county of New York, and State of New York, have invented certain new and useful improvements in Pen and Pencil Cases; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use the invention, I will proceed to describe it.

My invention consists in a novel manner of constructing a combined pen and pencil case, so that it may be adapted for use either as a desk or pocket pen and pencil.

Figure 1 is a longitudinal section of the article closed.

Figure 2 is a view of the same extended, with a portion shown in section; and

Figure 3 is a view of the pencil case, and extension handle detached from the main case, and having the extension handle shown in section.

A represents the main or outer case, which may be made of metal, hard rubber, or any other suitable material. Within this case A is secured the pen-holder C, which is made tubular, to permit the pencil case to be inserted through it, and to allow the former to slide over the latter as it is shoved back and forth, the pen-holder being operated by the sliding ring h, in the usual manner. The pencil case consists of a tube, b, which extends the whole length of the outer case A, and is attached permanently thereto at its lower end, b', by being soldered to a segmental ring n, which is secured to the case A, as shown in fig. 1. By making this ring, n, to occupy but only one side of the space between the outer case A and the tube b, an opening is left through which the pen-holder h protrudes, when shoved forward, as shown on the upper side of b, in fig. 1. The tube b has a smaller tube, a, which holds and carries the lead inserted within it, of nearly equal length; and from the side of this inner tube, a, near its upper end, projects a pin e, which works in a longitudinal slot in the upper portion of b, and also in a spiral slot in tube d, which fits over the upper portion of b, and turns loosely thereon. Sliding over, the pencil case is the extension handle, which consists of an inner tube, f, and an outer one, B. The inner tube f has a longitudinal slot, as shown in fig. 3, and a pin, o, is inserted through this slot into the tube d, by which means the handle is permitted to slide in and out over the pencil case, and at the same time by turning the handle the spirally slotted tube d is caused to turn with the handle, and thus to screw the pencil in or out. An outer shell or tube, B, of rubber or metal, is placed over the tube b, in order to cover the slot and give a finish to the handle. In order to hold this extension handle in position, and guide it when shoved out or in, it is connected to the upper end of the outer case A by means of an annular ring, i, as shown in figs. 1 and 2. In the upper end of the sliding handle B, is a cavity l, shown in fig. 1, to hold the pencil points, which is closed by an ornamental cap, c. When desired for use, the handle B is drawn out, as shown in fig. 2, and when it is desired to place it in the pocket, it is shoved in, as shown in fig. 1. By these means I produce a pen and pencil case that is very ornamental, extremely compact, and having the pen and pencil both located at the lower end so that they can both be used without inverting the holder.

Having thus described my invention, what I claim is—

The combined pen and pencil-holder, having pen and pencil both located at one end, and having the extension handle B arranged to operate as shown and described.

RICHARD H. RYNE.
